UNITED STATES PATENT OFFICE.

EDWARD C. NEWMAN, OF PORT JEFFERSON STATION, NEW YORK.

LOCOMOTIVE DRIVING BOX.

Application filed August 5, 1924. Serial No. 730,263.

This invention relates to locomotive driving boxes and particularly to an adjusting wedge therefor for taking up wear between the driving box and the pedestal of the side frame.

The principal object of the invention is the provision of a wedge which may be accurately adjusted as the driving box becomes expanded and out of line across the top due to the heat created by friction of the driving wheel axle running at a high rate of speed and carrying a tremendous weight.

Another object of the invention is to provide a wedge which will not stick to the driving box should the same become out of horizontal alignment but in the event that the same should accidentally become stuck, there is provided a means disposed below the wedge which will permit a limited amount of movement and said means is also employed for adjusting the position of the wedge.

With these and other objects in view, the invention resides in certain novel construction and combination and arrangement of parts, the essential features of which are hereinafter fully described, are particularly pointed out in the appended claims, and are illustrated in the accompanying drawing, in which:—

Figure 1 is a vertical sectional view of my invention applied to the driving box of a locomotive.

Figure 2 is a horizontal sectional view on the line 2—2 of Figure 1.

Figure 3 is a perspective view of the co-acting parts which constitute the wedge.

Referring more particularly to the drawing, the reference numeral 10 designates a portion of the side frame of a locomotive, and which is provided with the usual pedestal 11 having jaws 12, and between which jaws the driving box 13 is mounted. My improved wedge which is shown in its entirety as at 14 is inserted between one of the jaws 12 which is tapered and the adjacent wall of the driving box 13 as shown in Figure 1 of the drawing.

My improved wedge includes co-acting parts 15 and 16 which are constructed of steel. The part 15 comprises an inclined wall 17 on one face thereof, and a curved or arcuate shaped wall 18 on the opposite face thereof. The inclined wall 17 is adapted to co-act with one of the tapered jaws 12 of the

pedestal and is bounded on the vertical sides with flanges 19 which engage the sides of the pedestal to prevent lateral movement of the part. The part 16 is formed with a curved or arcuate shaped wall 20 corresponding to the curvature of the wall 18 of the part 11 and is adapted to co-act with the wall 18, while the opposite face of the part 16 is flat and receives a wear plate or shoe 21. The plate 21 is made of brass or other relatively soft material and is attached to the flat face of the part 16 by copper rivets 22 which have their heads counter-sunk whereby the rivets will wear simultaneously with the plate 21. The wear plate 21 co-acts with the vertical wall of the driving box when the wedge is in position.

From the foregoing description, it will be seen that the parts 15 and 16 are placed in co-acting position and inserted in the space between the tapered jaw 12 and the adjacent wall of the driving box. The wedge is inserted for a distance sufficient to support the driving box in its proper horizontal position, and upon the wear of the plate 21, the same may be driven or moved further toward the top of the pedestal to compensate for the wear usually caused by friction. When the plate 21 has been completely worn, the same may be removed and a new plate substituted therefor.

Disposed below the wedge is an adjusting means 23 for use in adjusting the wedge and upon which the wedge rests. The means 23 comprises a bracket 24 which is bolted or otherwise secured as at 25 to the lower edge of the side frame 10. Threadedly mounted in the bracket is a tensioning spring adjusting nut 26 having a smooth bore therein and through which passes a rod 27. The rod 27 is threaded midway between its ends as at 28 for the reception of lock nuts 29 which nuts are held against rotation by the side walls of the bracket. The lock nuts are normally jammed against the side frame by a spring 30 which places the rod under a slight tension after the same has been adjusted against the part 15 of the wedge by rotating the rod. The free end of the rod is provided with a wrench surface for accommodating an instrument which will permit the easy turning of the rod. It will be seen that one end of the spring abuts the nuts while the other end is seated against the adjusting member and which member may be moved longitudinally.

dinally to vary the tension of the spring. The bracket is provided with stop shoulders 31 which are arranged in the path of movement of the nuts whereby to limit the downward movement of the wedge should the same become accidentally stuck to the driving box. The spring 30 will tend to absorb any shock or pounding upon the dropping of the driving box out of its proper horizontal position.

It will therefore be seen that I have provided an adjusting wedge which may be easily applied to the driving box of a locomotive and which will take up the wear usually caused between frictional contact of the pedestal of the side walls of the driving box.

While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my in-

vention limited only by the appended claim. What is claimed as new is:—

1. In a device of the class described, the combination with the side frame of a locomotive, jaws formed therein, a driving box between said jaws, a wedge including a pair of co-acting separable parts, one of said parts co-acting with one of the jaws and the other of said parts having a wear plate thereon of relatively soft material for co-action with the adjacent side wall of the driving box for compensating for the wear between said driving box and said jaws.

2. A wedge comprising a pair of parts, one of said parts having a concaved surface on one face and an inclined surface on the opposite face, the other of said parts having a convex surface on one face for co-action with the concave surface on the other part, and a wear plate secured to the opposite face of said last part, substantially as and for the purpose specified.

In testimony whereof I have affixed my signature.

EDWARD C. NEWMAN,
